UNITED STATES PATENT OFFICE.

SAMUEL W. MANSFIELD, OF ST. LOUIS, ASSIGNOR OF ONE-HALF TO OLIVER C. KINLEY, OF MOBERLY, MISSOURI.

COMBINED HEATING, COOKING, AND DRYING APPARATUS.

SPECIFICATION forming part of Letters Patent No. 243,929, dated July 5, 1881.

Application filed April 6, 1881. (No model.)

To all whom it may concern:

Be it known that I, SAMUEL W. MANSFIELD, of St. Louis, in the State of Missouri, have invented a certain new and useful Improvement 5 in Combined Heating, Cooking, and Drying Apparatus, of which the following is a full, clear, and exact description, reference being had to the accompanying drawings, forming part of this specification.

10 My improvement relates to a device for heating the air of a room, for cooking food, and for drying fruit, grain, vegetables, and clothing; and the purpose and object of my invention is to secure more convenience and cleanliness in 15 cooking and drying, and a more complete distribution of the heated air in the room, the same being in the nature of an ornamental piece of cabinet-furniture, preferably rectangular in shape and constructed of finished wood lined 20 with tin or other sheet metal, or I may make the case or cabinet of sheet or cast iron.

My improvement consists in the construction and arrangement of parts, as hereinafter set forth and claimed.

25 In the drawings, Figure 1 is a perspective view of my improvement, showing one of the cabinet-doors standing open. Fig. 2 is a vertical longitudinal section. Fig. 3 is a vertical section at line x x , Fig. 4. Fig. 4 is a horizontal section on line x' x' , Fig. 2; and Fig. 5 is a similar view on line x^2 x^2 , same figure.

A is the case or cabinet, both sides of which are provided with doors B, preferably double. The sides being duplicates, either may be used 35 as front. The ends of the cabinets and the upper parts of the doors B are provided with glass windows, as shown, for the admission of light. Under the windows, in the ends of the cabinet, inside, is a small metal shelf, C, which 40 is arranged to be removed when not in use, thus giving more space for drying fruit or clothing. This shelf C is for supporting cooking-vessels, &c., thus keeping victuals warm until required for the table. The upper part of the 45 cabinet is arranged, as shown at E, to receive bars and trays for drying clothing or fruit, grain, vegetables, &c. F is an opening in the top of the cabinet, through which the heated air escapes into the room, warming the apartment.

At one end of the cabinet is located a cast-iron fire-box, G, and at the other end, and connected with the fire-box, is a cast-iron oven, H. The products of combustion pass out from the fire-box through the flue I between the top 55 of the oven and the cooking-surface J and out into the smoke-pipe K, when the damper L, which is of common construction, is open; or the products of combustion may, by closing the damper L, be made to pass down through 60 the flues M, located at the back of the oven, between it and the outer case, A, thence under the oven through flues N, and thence back through central return-flue O to the smoke-pipe K, thus heating the oven for the purpose 65 of roasting or cooking.

The fire-box G is provided with a front or face-plate, G', to which two doors, g and p, are hinged, the upper one, g, of which opens into the fire-box G, and the lower one, p, into the 70 ash-pit P, below. The ash-pit P contains a removable ash-pan, P', for receiving the ashes, cinders, &c., as they drop from the fire-box G. One-half or thereabout of the bottom of the fire-box is a removable grate, g', the other half, g², being a solid bed-plate. The sides g³ of the fire-box G incline outward toward the top. Thus the fire-box is considerably wider at the top than at the bottom. This form of fire-box has important advantages, as it gives a large amount 75 of heating-surface above, and yet concentrates and delivers the ashes and cinders into the ash-pan beneath, from where they can conveniently be removed.

The inside of the oven H has two compartments, formed by means of the removable horizontal shelf or grate H'. The oven has door or doors H² hinged upon each side, so that when the cabinet is turned or changed it does not interfere with the free access to the oven. 85

Q is an opening in the outer wall or case, A, which allows access to the flues O N beneath the oven H, for the removal of accumulated dirt, soot, or ashes. The opening Q is closed 90 by means of a small door, q.

Just above the fire-box and oven, and forming the top of the former, is detachably fastened the cooking plate or surface J, which is supplied with pot-holes j' for the reception of cooking vessels. 95

R is the metal bottom of the ash-pit, extending beneath the bottom of the oven and forming the bottom of the cabinet. In the bottom R are openings *r* on each side of the ash-pit 5 for the admission of air to be heated.

On each side of the ash-pit, fire-box, and oven is a single metal shield, S, whose upper edges connect with the cooking-surface J, with the metal bottom R, and the ends of the metal-lined case A, thus closing in the fire-box, ash-pit, and oven, except the oven-doors, openings being made in the shields S to allow the opening and closing of said doors.

The air to be heated enters through openings *r* and passes up through flues T on each side of the ash-pit and fire-box between them and the metal shield S, and passes out through openings *t* in the shield, near the cooking-surface J, thence up through the cabinet and out 20 through opening F in the top of the cabinet into the room in which the device is located. There are also openings *r'* (see Fig. 4) in the metal bottom R between the oven and the outer wall, A, of the cabinet, which furnish a greater supply of air to be heated and secure a more 25 rapid circulation of the heated air in the room.

The cooking-surface J is covered with a metal-shield, U, when the apparatus is to be used for drying fruit or clothing, thus protecting them from the direct radiated heat. 30

Both sides of the cabinet being nicely finished and provided with doors, it may be turned or changed from one room to another, using either side as front, and thereby adapting it to any room regardless of the position of the 35 flue.

The following is what I claim as new and desire to secure by Letters Patent:

The combination of the oven H, fire-box G, 40 ash-pit P, shields S, with openings *t*, and cooking-surface J, the whole forming flues I, M, N, O, and T, and being inclosed within a metal-lined or metal case or cabinet A with duplicate sides, as set forth, and provided with openings *r* *r'* and F, substantially as and for 45 the purpose set forth.

SAMUEL W. MANSFIELD.
